UNITED STATES PATENT OFFICE.

ASHLEY P. PECK, OF MILWAUKEE, WISCONSIN, ASSIGNOR TO THE BULLOCK ELECTRIC MANUFACTURING COMPANY, A CORPORATION OF OHIO.

COMMUTATOR NECK OR LEAD.

No. 903,881.

Specification of Letters Patent.

Patented Nov. 17, 1908.

Application filed November 9, 1905. Serial No. 286,476.

To all whom it may concern:

Be it known that I, ASHLEY P. PECK, a citizen of the United States, and resident of Milwaukee, in the county of Milwaukee and State of Wisconsin, have invented certain new and useful Improvements in Commutator Necks or Leads; and I do hereby declare that the following is a full, clear, and exact description thereof.

10 My invention relates to commutator necks or leads.

Heretofore in building direct-current dynamo-electric machines, considerable trouble has been experienced because of the vibration of the commutator leads or necks, this vibration often being sufficient to cause adjacent commutator necks to engage to short-circuit one or more of the armature coils. This has been especially the case in large 20 machines which necessitate long commutator necks. To avoid this vibration, it has heretofore been found necessary to employ special bracing auxiliary devices, such as fish cord lacing or insulating spacers between the 25 adjacent necks.

It is the object of my invention to so construct the commutator necks that they will be sufficiently strong inherently to withstand any tendency to vibrate and thereby obviate 30 the necessity of employing auxiliary bracing devices. This result is accomplished by making each of the commutator necks of a cross section which is other than a straight line, so that in order to vibrate in any direction, 35 the metal composing the neck will have to be bent edgewise to a greater or less degree.

The particular novel features of my invention will appear from the following description and will be pointed out in the 40 claims.

Figure 1 is a plan view of a commutator neck or lead embodying my invention; Fig. 2 is an end view of the same, partly in section; Fig. 3 is a transverse sectional view 45 on the line 3—3 of Fig. 1; Fig. 4 is a similar sectional view showing a somewhat modified construction; and Fig. 5 is a partial end elevation of an armature and a commutator provided with my improved necks or leads.

50 Referring to the drawings, 1 and 2 represent two parallel strips of sheet copper or other suitable material, held together by rivets 3 to form the neck or lead. These strips are preferably punched out and rolled 55 into the desired form in one operation. Each

of the strips is formed with a central longitudinal rib or corrugation 4, as shown in Figs. 1, 2 and 3, thus making the strips substantially U-shaped in cross section, whereby the two strips may be nested together as 60 shown. The corrugation 4 extends along the central portion of the strips 1 and 2 nearly to each end thereof, one end of the strips being bent as shown to receive the free ends 6 of the armature windings 7, while the opposite end may be left flat for connection to the commutator bars 8, as shown in Fig. 5.

In Fig. 4 the two strips are shown as having oppositely projecting edges 5—5, each strip thus being substantially U-shaped in 70 cross section, and the two strips placed together base to base.

The armature windings and the commutator may be of any desired type, as *per se* they form no part of my present invention. 75

By making my commutator neck or lead so that throughout a portion of its length the cross section is other than a straight line, a much greater stiffness or rigidity is given to the neck, thereby eliminating or greatly reducing vibration and rendering accidental electrical contact between adjacent necks impossible. Moreover by reducing or avoiding vibration of the necks, crystallization of the copper or other metal forming the necks is 80 prevented or greatly diminished, thereby lessening the liability of fracturing the necks.

My invention is also applicable in other electrical apparatus although it is primarily designed for use as a commutator lead or 90 neck.

What I claim is:—

1. A commutator neck or lead composed of a plurality of similarly corrugated strips of sheet metal nested and riveted together. 95

2. A commutator neck or lead composed of a plurality of strips of sheet metal fastened together, each strip being corrugated lengthwise.

3. A commutator neck or lead composed of a plurality of strips of sheet metal fastened together, each strip being substantially U-shaped in cross section. 100

4. A commutator neck or lead composed of a plurality of strips of metal fastened together, each strip having a transverse section two sides of which are substantially parallel and are other than straight lines. 105

5. In combination, an armature coil, a commutator bar, and a neck or lead com- 110

posed of a plurality of lengthwise corrugated strips of metal joining them.

6. In combination, an armature winding, a commutator, and necks or leads connecting them, said necks or leads being composed of strips of metal substantially U-shaped in cross section.

7. In combination, an armature coil, a commutator bar, and a neck or lead connecting them, said neck or lead being composed of a plurality of strips of metal fastened together and each having a transverse section two sides of which are substantially parallel and are other than straight lines,

8. In combination, an armature coil, a 15 commutator bar, and a neck or lead connecting them, said neck or lead comprising a plurality of strips of metal having interfitting elevations and depressions.

In testimony that I claim the foregoing I 20 have hereunto set my hand at Milwaukee in the county of Milwaukee and State of Wisconsin in the presence of two witnesses.

ASHLEY P. PECK.
